UNITED STATES PATENT OFFICE.

HALDOR K. SOLBERG, OF CLARKFIELD, MINNESOTA.

DESIGN FOR A MEDAL OR SIMILAR ARTICLE.

SPECIFICATION forming part of Design No. 30,643, dated May 2, 1899.

Application filed April 4, 1899. Serial No. 711,738. Term of patent 7 years.

To all whom it may concern:

Be it known that I, HALDOR K. SOLBERG, a citizen of the United States, residing at Clarkfield, in the county of Yellow Medicine and State of Minnesota, have invented and produced a new and original Design for a Medal or Similar Article, of which the following is a specification.

This invention relates to a new and original design for a medal or similar article; and it has for its object to provide a design of this character that shall be both useful and ornamental.

The leading features of the design are a medal or similar article provided upon the obverse side thereof with a bust portrait of the great reformer and founder of the Lutheran church and upon its reverse side with a picture of a church building, associated with the representation of an open Bible and a brilliant star in the sky, representing the "Star of Bethlehem."

The minor features of the design are the arrangement of the open Bible below the picture of the building and partly concealed thereby, the representation of clouds within the sky above the spires of the church building, and the representation of the star.

In the drawings, Figure 1 is a plan view of the obverse side of a medal or similar article embodying the herein-described design. Fig. 2 is a similar view of the reverse side thereof.

Referring to the accompanying drawings, the numeral 1 designates a medal or similar article of a circular configuration, having a

circular marginal band 2 upon both the obverse and reverse sides thereof. Within the circular field, upon the obverse side of the medal or similar article, the latter is provided with a bust portrait of Martin Luther, who is historically known as the great reformer and founder of the Lutheran church. Upon its reverse side the circular body of the medal or similar article is provided with the picture of a church building having a plurality of gables or spires and represented as being of a modern type of architecture. Immediately below the picture of the church appears the representation of an open Bible, partly concealed by the building, while within the upper portion of the circular field, above the spires of the church building, clouds are represented within the sky, and also a brilliant star, symbolic of the star known to those of the Christian faith as the "Star of Bethlehem." The design matter upon the reverse side of the medal or similar article is completed by the representation of a number of smaller stars within the sky.

What is claimed is—

The design for a medal or similar article, herein shown and described.

In testimony that I claim the foregoing as my own I have hereto affixed my signature in the presence of two witnesses.

HALDOR K. SOLBERG.
